(57) **CLAIM**

The ornamental design for a ceiling fan, as shown and described.

DESCRIPTION

FIG. 1 is a lower front side perspective view of the ceiling fan design.

FIG. 2 is an upper front side perspective view of the ceiling fan design of FIG. 1.

FIG. 3 is a front side view of the ceiling fan design of FIG. 1.

FIG. 4 is a left side view of the ceiling fan design of FIG. 1.

FIG. 5 is a rear side view of the ceiling fan design of FIG. 1.

FIG. 6 is a right side view of the ceiling fan design of FIG. 1.

FIG. 7 is a top view of the ceiling fan design of FIG. 1; and, FIG. 8 is a bottom view of the ceiling fan design of FIG. 1. The broken lines showing of the ceiling fan blades and ceiling canopy in FIGS. 1-8 are for illustrative purposes and form no part of the claimed design.
